JOHN W. COAST, JR., OF TULSA, OKLAHOMA, ASSIGNOR TO THE PROCESS COMPANY, OF TULSA, OKLAHOMA, A CORPORATION OF MARYLAND.

APPARATUS FOR CRACKING HYDROCARBONS.

1,307,724.

Specification of Letters Patent. Patented June 24, 1919.

Application filed October 6, 1917. Serial No. 195,066.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in Apparatus for Cracking Hydrocarbons, of which the following is a full, clear, and exact description, reference being had to the accompanying 10 drawing, forming a part of this specification.

This invention relates to improvements in apparatus for cracking hydrocarbons, and more particularly to a structure involving 15 the use of a fire-heated cracking still wherein a body of hydrocarbon oil is confined under pressure.

While the oil is undergoing distillation under high pressure and at a high temperature, a heavy carbonaceous substance known as coke and coke-forming matter drops by 20 gravity and settles on the bottom of the still. This heavy substance is a heat insulator and it is usually permitted to accumulate 25 on the hot still bottom, directly above the fire, thus preventing the free transmission of heat from the still bottom to the oil. One of the important problems in this art lies in the elimination of the danger 30 and expense due to the presence of large bodies of coke-forming matter on the hottest parts of cracking stills. In following the ordinary practice it is necessary to increase 35 the temperature of the still bottom as the cracking operation progresses, so as to maintain the oil at the necessary high temperature. As a consequence, the still bottom is liable to be overheated and become red hot, and in this event some immediate steps must 40 be taken to avoid a rupture at the overheated portion of the still. The still may be cooled and the operation discontinued for 45 the purpose of removing the residue, or the cracking operation can be continued at a lower temperature. Obviously, both of these steps are very undesirable.

The accumulation of coke-forming matter on the hottest part of the cracking still is therefore a source of danger, and it results 50 in many losses. A waste of fuel results from the transmission of heat through the thick body of insulating matter, and the life of the still is decreased by exposure to high temperatures. However, the greatest loss is

due to the fact that the necessary high pressure and high temperature cannot be maintained for a period long enough to obtain the maximum yield from the heavy oil. By prematurely stopping the operation on account of the presence of the coke-forming 55 matter, a very large volume of unconverted and partially converted hydrocarbons remain in the cracking still as residue, instead of being transformed into the desired low boiling point product.

My objects are to avoid the danger and heat losses which have resulted from the presence of coke-forming matter in large cracking stills; and to crack and distil the oil very rapidly, thus increasing the capacity of the still. However, a most important advantage lies in the greatly increased yield of low boiling point hydrocarbons, which I obtain by maintaining the oil at the necessary high pressure and temperature, until it no longer responds readily to the cracking treatment.

In the preferred form of the invention, all of the foregoing advantages are obtained by confining a body of hydrocarbon oil in 80 a large horizontal cylindrical fire-heated cracking still, the arcuate bottom of the still being exposed to the fire; maintaining the contents of the still at a high pressure and at a high temperature, and at the same time continually sweeping coke-forming matter from one end of the still to the other. One end of the still bottom is protected from the fire and the coke-forming matter is swept 85 along the still bottom and permitted to accumulate at said protected end. Therefore, the heat is transmitted freely from the fire heated still bottom to the oil, and the high temperature can be maintained without overheating the still. In addition to the advantage of greatly increasing the yield of low boiling point fractions, the cracking operation can be carried on continuously for a considerable period of time, by introducing 90 a fresh charge into the still without removing the residue.

Figure I is a diagrammatical view of a cracking apparatus constructed in accordance with my invention.

Fig. II is an enlarged fragmentary longitudinal section of the still.

Fig. III is an enlarged transverse section of the still.

The apparatus shown to illustrate the invention comprises a large horizontal cylindrical cracking still 1, arranged above a heating chamber 2 and connected, by means of a vapor pipe 3, to an air cooled reflux condenser 4. 5 designates a vapor pipe leading from the reflux condenser to a water cooled condensing coil 6 from which the low boiling point product is recovered.

10 The apparatus herein shown is particularly adapted for use in cracking high boiling point products of distillation such, for example, as distillates or residues resulting from the distillation of crude petroleum.

15 The oil to be treated may be introduced into the still in any suitable manner, and any desired pressure may be obtained by regulating a valve 7, preferably arranged in the vapor pipe 5. The pressure in the still is

20 greater than three atmospheres, preferably about 80 pounds per square inch, and the temperature of the contents of the still preferably ranges from about 600° F. to 800° F.

25 A very large area of the arcuate still bottom is exposed directly to the fire, but the end portions of said bottom are protected from the fire by the walls 8 upon which the still is seated.

While the oil is undergoing distillation under a high pressure and at a high temperature, heavy coke-forming matter will accumulate in the still and tend to settle on the arcuate bottom, directly above the fire. To avoid the danger and expense heretofore incurred by the presence of the coke-forming matter, at the same time greatly increasing the yield of low boiling point fractions, the coke-forming matter is constantly swept to one of the protected end portions of the still bottom.

The continuous, flexible, endless sweeping device comprises a pair of endless sprocket chains 9, arranged longitudinally of the still and fitted to sprocket wheels 10 near the ends of the still. The sprocket wheels 10 support the endless chains 9. Arcuate bars 11, arranged transversely of the still, are connected to the pair of sprocket chains 9. 12 designates scraper blades conforming to the configuration of the arcuate still bottom, and provided with fingers 13 which extend through guides or bearings 14 on the arcuate bars 11. The fingers 13 are rigidly secured to the blades 12 and slidably mounted in the bearings 14. Pins 15, passing through the fingers 13, prevent the latter from accidentally dropping out of the bearings 14. Each arcuate scraper carrying bar 11 is preferably provided with a series of 60 the blades 12, as shown in Fig. III.

The means for actuating the endless sweeping device comprises a power shaft 16 passing through a stuffing box 17 at one end of the still, and provided with an operating wheel 18 (Fig. I) at the exterior of

the still. A worm 19, at the inner end of the power shaft 16 meshes with a wheel 20 on the shaft 21, to which two of the sprocket wheels 10 are secured.

When the apparatus is in operation, the 70 shaft 16 is driven continually so as to move the endless sweeping device in a continuous endless course, as indicated by arrows in Fig. II. The lower portion of the sweeping device travels along the fire heated bottom 75 of the still, in one direction only, thereby constantly sweeping coke-forming matter to a protected end portion of the still bottom, immediately above one of the walls 8. The coke-forming matter will, therefore, 80 accumulate at a part of the still not exposed directly to the fire, and it will not in any way interfere with the transmission of heat from the fire to the oil. The cracking operation can, therefore, be continued long 85 enough to obtain a greatly increased yield from the heavy oil, and since the danger of overheating the still is almost entirely eliminated, a very hot fire can be maintained and the oil can be distilled very rapidly. 90

23 designates a coke-receiving chute arranged within the still and surrounded by the endless sweeping device. This chute is so inclined that the coke-forming matter falling thereon will be discharged at the 95 protected end portion of the still, where the main body of coke is permitted to accumulate. An arcuate brush 24 is secured to the upper portion of the still for the purpose of removing coke-forming matter from the 100 scrapers 12. The brush 24 extends into the path of the scrapers 12, so as to remove the coke-forming matter from the scraping edges. After forcing coke-forming matter to a protected end of the still, the scrapers 105 move upwardly as indicated in Fig. II, therefore, moving horizontally to the opposite end of the still, and then downwardly to the still bottom. The coke-forming matter dropping from the scrapers at the upper 110 portion of the still, falls onto the chute 23.

I claim:

1. In an apparatus for cracking hydrocarbons, a horizontal cylindrical fire-heated cracking still, a large area of the bottom of the still being exposed to the fire and one end portion of said bottom being protected from the fire, a continuous endless sweeping device mounted in said still and engaging the bottom thereof, means for transmitting power to said sweeping device so as to sweep coke-forming matter to the protected end of the still, and a chute surrounded by said endless sweeping device, said chute being inclined to direct coke-forming matter to said 125 protected end portion of the still

2. In an apparatus for cracking hydrocarbons, a fire-heated cracking still, a continuous endless sweeping device mounted in said still and engaging the bottom thereof, 130

means for transmitting power to said continuous endless sweeping device, and a coke-receiving device surrounded by said endless sweeping device to receive the coke-forming matter passing from the upper portion of the sweeping device.

3. In an apparatus for cracking hydrocarbons, a fire-heated cracking still, a continuous endless sweeping device mounted in said still and engaging the bottom thereof, means for transmitting power to said continuous endless sweeping device, means for removing coke-forming matter from the upper portion of said endless sweeping device, and a coke-receiving device surrounded by said

endless sweeping device to receive the coke-forming matter passing from the upper portion of the sweeping device.

4. In an apparatus for cracking hydrocarbons, a fire-heated cracking still, a continuous endless sweeping device mounted in said still and engaging the bottom thereof, means for transmitting power to said continuous endless sweeping device, and a brush secured in said still above said sweeping device to remove coke-forming matter therefrom.

In testimony that I claim the foregoing I hereunto affix my signature.

JOHN W. COAST, JR.
